(57) **CLAIM**

The ornamental design for a snowman mold, as shown and described.

DESCRIPTION

FIG. 1 is a perspective view showing a generally curved top, middle, and bottom portion of the new snowman mold design;

FIG. 2 shows each portion of the new snowman mold design, as shown in FIG. 1, separated into a first half section having a mating flange along its periphery and a second half section having a corresponding mating flange along its periphery; the top, middle, and bottom portions each having a lower opening, and the middle and bottom portions each having a top opening;

FIG. 3 is a perspective view of the first half section and the second half section of each portion of the new snowman mold stacked/nested as shown; and,

FIG. 4 shows a half section of the top, middle, and bottom portion packed with snow, the snow forming no part of the new snowman mold design.
